IRONING AND PRESSING MACHINE

Calvin John Shimer, Fort Wayne, Ind., assignor
to The Boss Manufacturing Company,
Kewanee, Ill.

Original application May 8, 1928, Serial No.
276,114. Divided and this application January
16, 1931. Serial No. 509,203

36 Claims. (Cl. 68—13)

This invention relates to ironing and pressing machines, and while useful in various connections it is primarily adapted for ironing and pressing workmen's gloves, mittens, and gauntlets.

Heretofore in the manufacture of workmen's gloves, which are usually constructed of fabric or fabric in association with other materials, very little attention has been given to the appearance of the gloves, and from the time the gloves are formed until they are stacked and placed in cartons the gloves handled several times. The handling of the gloves in this way (aside from the possibility of soiling) oftentimes causes wrinkling, and the amount of mussing or wrinkling is of course increased where the gloves have not been subjected to a preliminary ironing or pressing operation, with the result that the boxed gloves, under existing practice, are frequently untidy in appearance.

In my copending application, Serial No. 276,114, filed May 8, 1928, resulting in Letters Patent 1,855,846, dated April 26, 1932, and of which application the present application is a division, there is illustrated and described a machine for overcoming the above objections, including means whereby the gloves may be arranged on a conveyor and fed through an ironing machine from which they are discharged into operative position with respect to the stacking mechanism, the operation of the stacking mechanism being controlled by the movement of succeeding gloves through the ironing mechanism, and the stacking mechanism being designed to properly register the gloves with a suitably supported box or carton; and when the desired number of gloves has been assembled, with respect to the box, suitable indicating mechanism, such as a bell, is designed to automatically apprise the operator of the fact, and the operator then removes the box with the contained gloves.

The present application relates more particularly to the means for ironing and pressing the gloves previous to the boxing and stacking operation, together with means for delivering the gloves to and from the ironing and pressing mechanism, it being obvious that the ironing and pressing mechanism and associated parts are useful in connections other than with the particular stacking and boxing mechanism illustrated and described in my copending application.

The present application also is directed to means associated with the ironing and pressing mechanism for counting the gloves as pressed, whereby the indicator or signalling mechanism

will be automatically operated and apprise the operator after a certain number of the gloves have been pressed, thus obviating the necessity of manually handling the gloves in counting the same previous to the boxing operation, it being the custom to box the gloves with a definite number in each box.

It is obvious, of course, that while the ironing, pressing, and conveyor mechanisms, as well as the indicating mechanism, herein described, are intended primarily for operation upon gloves and particularly workmen's gloves, these various mechanisms herein described and claimed are susceptible of a wide range of uses and adaptations and are not restricted to any specific type of stacking and boxing mechanism, such as constitute the subject-matter of claims in my copending parent application hereinabove referred to.

The various improvements and novel details of construction and arrangement of parts of the present invention will be more fully understood from the description to follow when read in connection with the accompanying drawings, which form a part hereof, and wherein is disclosed for the purpose of illustration a convenient and satisfactory embodiment of the invention, it being understood that minor details in the construction and arrangement of parts may be resorted to without departing from or avoiding the general appearance or the spirit of my invention.

In the drawings:

Figure 1 is a side elevation of a machine made in keeping with my invention;

Figure 2 is an opposite side perspective;

Figure 3 is a vertical longitudinal section, the carriages and other parts of the stacking mechanism being omitted;

Figure 4 is a side elevation of the machine with the parts removed; and

Figure 5 is an enlarged top plan of the machine, with parts removed and other parts broken away;

Figures 6, 7, 8, and 9 are detail views.

In the description, it will be understood that like reference numerals refer to corresponding parts throughout the several views of the drawings.

The main framework for the machine includes side walls, preferably of metal, and generally designated by the reference characters A and B, and for convenience in the reading of the drawings that side of the machine having the side wall A will be referred to as the front side wall, and that side of the machine having the wall B will be referred to as the rear side of the machine. Assuming that gloves are the articles to be ironed

and pressed, the walls A and B are spaced from one another a distance slightly in excess of the normal length of the gloves to be operated upon, and these walls are connected to a bottom wall C. 5 The framework as thus far described may, if desired, be supported at any convenient height by upright standards or the like (not illustrated), or may rest directly upon a work table, bench, or other suitable support, conveniently arranged adjacent 10 the glove forming machine, which latter constitutes no part of the present invention and is therefore not illustrated.

The side walls A and B have adjacent the bottom thereof elongated extensions 1 and 1^a, respectively, adapted for connection with the side walls of a glove stacker frame or chute to be hereinafter described. The top edges 2 and 2^a of the side walls conveniently incline upwardly towards what may be said to be the forward end 15 of the machine and connect with curved parts 3 and 3^a which in turn connect with the projecting arms 4 and 4^a.

The side walls A and B are adapted to support therebetween the glove conveyor and pressing mechanism. 5 is a relatively large main roller which projects between the side walls A and B and has a suitable shaft 6 projecting at its ends through suitable bearings in said side walls A and B. Positioned upon that projecting end of the shaft at the front side of the machine is a suitable drive wheel 7 which is adapted to be rotated in any desired manner, as by hand manipulation, but which in the present embodiment of the invention conveniently takes the form of a pulley 25 having a peripheral groove 7^a adapted to receive a drive belt 8 preferably driven by a suitable motor of any convenient construction, as illustrated in Figure 5. The relatively large roller 5 may be termed a main presser roll; and operatively associated with the latter is an auxiliary presser roll 35 10, which latter, however, is normally spaced out of contact with the main presser roll 5. The auxiliary presser roll 10 has shaft extensions 11 mounted in suitable bearings taking the form of slotted ways 12 in the side walls A and B of the frame adjacent the rear upper end thereof.

A suitable spring 13 connects at one end with an arm or bracket on the shaft 11, and at its opposite end to the side wall A, said spring tending to normally exert inward pressure on the auxiliary presser roll whereby the shaft 11 for said roll will assume a position in contact with the lower edge of the slotted ways 12. An upper guide roll 14 is mounted upon a suitable shaft 15 having bearings in the side walls A and B. A guide roller 16 projects between the side frame extensions 4 and 4^a and is freely mounted for rotation on suitable pintles 17 projecting through slotted ways 18 in said side frame extensions, and said pintles are adapted to be secured in adjusted positions along said slotted ways as by securing bolts or the like 50 19. A lower auxiliary guide and presser roll 20 projects between the side walls A and B, said roll being mounted upon a shaft 21 the extended ends of which are positioned in slotted ways 22.

A lower guide roll 23 is provided, having a shaft 24 projecting through slotted ways 25 in the side walls A and B; and suitable springs 26 connecting at one end to pins 27 on the side wall frames and at the opposite end to a projecting lug or bracket sleeved upon the shaft extension 24, serve to exert constant spring-pressure in a direction towards the extensions 1 and 1^a of the side frame parts.

A combination endless glove-carrier and presser belt 28 is provided, the same being construct-

ed of any suitable material but being preferably of leather or the like and having a relatively smooth glove-receiving surface. This endless belt extends over the main presser roll 5 and the guide roll 16 and is adapted to travel under the influence of the driving pulley 7 in the direction of the arrow as illustrated in Figure 3.

Any normal slack in the belt 28 is taken care of through the medium of the adjustable connection 18-19 for the guide roll 16. The combined feed and presser belt 28 is of a width preferably slightly less than the space between the side walls A and B and is wider than the length of the gloves to be conveyed and ironed, and the upper run of the belt constitutes an extended movable receiving shelf adapted for the continuous deposit thereon of the gloves by the operator who receives the same from the usual "hot form" 90 of the glove-forming machine and places the gloves while still in a heated condition on said movable shelf formed by the belt 28, in alternate relation; that is to say, the left-hand gloves projecting towards one side wall and the right-hand gloves projecting towards the opposite side wall ("rights" and "lefts" being in alternation), so 95 that the gloves as delivered to the stacking mechanism will be arranged in paired relation.

An auxiliary endless belt 29 projects around the guide rolls 14 and 23 and over the auxiliary presser rolls 10 and 20, whereby the inner run of 105 said belt will lie in contact with that portion of the presser belt 28 in engagement with the main presser roll 5.

The upper part of the endless belt 29 below the main presser roll 5 will constitute a delivery 110 or discharge conveyor for the ironed and pressed gloves, whereby to deliver said gloves to the transfer assembly and stacking mechanism to be later described.

It being assumed that the gloves have been arranged in alternate relation upon the upper portion of the belt 28 which constitutes a feed for the gloves, the latter are delivered one after another between the opposed adjacent faces of the belts 28 and 29, and by reason of the pressure 115 exerted upon said gloves by the belts, through the cooperative action of the presser rolls 5, 10, and 20, said gloves will be ironed or pressed whereby to remove wrinkles and the like, and will be delivered in flattened, smooth condition by 125 130 that portion of the belt 29 arranged below the main presser roll 5. It will be noted in this connection that the gloves will be maintained in spaced relationship while being fed through the ironing or pressing mechanism.

The glove transfer, assembly, and stacking mechanism will now be described.

A runway or chute comprises a bottom wall 30 and side walls 31, the rear portions of the side walls being fitted within and secured to the forward extensions 1 and 1^a of the side walls of the main frame. The side walls at their point of connection with the main frame side walls are separated from one another a distance somewhat in excess of the length of the gloves and have inwardly inclined parts 31^a connecting with separate portions 31^b, which latter are spaced from one another a distance substantially the length of the glove. The enlarged space between the rear portions of the side walls 31, which as stated is somewhat greater than the length of the gloves, will be of assistance in the movement and assembly of the gloves in the chute under the stacking action; and the intermediate inclined portions 31^a assist in the aligning of the gloves 145 150

for reception in the reduced space provided by those portions of the side walls 31b, the gloves substantially filling this latter space, as noted.

It is desirable that the gloves be assembled in the chute or runway in an upright or edgewise condition, with one edge of the glove in contact with the bottom wall of the runway; and to this end means is employed to insure proper assembly and positioning of the gloves as they leave the delivery portion of the belt 29 after the ironing operation. A transfer paddle or guide plate 32 is pivotally mounted so that in one position the upper end thereof will contact with that portion of the belt 29 projecting around the guide roll 23, at which time the paddle will assume an inclination, thereby constituting in effect a continuation of the general curvature or inclination of the adjacent portion of the delivery belt. It will thus be appreciated that the foremost glove on the delivery run of the belt, which at this time is spaced from the next adjacent glove, will be delivered from said belt directly onto the paddle or plate 32 and slide down the latter, whereby one edge of the glove will rest upon the bottom wall of the stacking chute. The glove is retained temporarily in this position by a movable abutment comprising an angle plate one portion 33 of which, when the paddle plate 32 is in the position just described, will project upwardly as illustrated in Figure 3, for instance; and the other portion 34 of which abutment at this time projects substantially horizontally and in contact with the bottom wall of the stacking chute and beneath the lower edge of the paddle or guide plate 32. The paddle or guide plate also constitutes a transfer medium whereby to deliver the gloves in stacked relation against one another in the chute and also serves to impart longitudinal movement to the gloves along the runway provided by the bottom wall of the stacking chute. Convenient means for operating the transfer paddle is as follows:—Projecting downwardly from the side wall extensions 1 and 1^a are hangers 35 and 36 adapted for supporting therebetween elongated guide bars 37, one at each side of the machine, and sleeved upon these guide bars are suitable carriages 38a, 38b adapted to move longitudinally thereupon. The guide or panel plate 32 has downward side projections 32a passing through slots in the bottom wall and having laterally projecting pintles 40 mounted upon bearings on said carriages 38a and 38b, whereby the paddle or plate 32 is adapted for sliding movement along the chute with the carriages and is also adapted for swinging movement about the axis provided by said pintles 40.

Supporting brackets 41 project outwardly and downwardly from the side frames 1 and 1^a, being secured to the latter as by bolts or the like 42, at a point between the hangers 35 and 36 and passing to the outside of the elongated carriage guides 37. These brackets 41 are adapted to support therebetween a transverse rotatable shaft 43. Affixed to that side of the shaft 43 projecting to what has been termed the front side of the machine, is an arm 44 projecting upwardly and pivotally connected at its free end as by a pin 45 to a horizontally extending arm 46 the arm 46 being connected with the carriage 38a to impart movement to the latter. It will thus be seen that according to the rotation of the transverse shaft 43 in one direction or another, the carriage will have movement imparted thereto, either forward or backward, along the guide bars 37. Assuming that this transverse rock-shaft is moved in a direc-

tion to impart forward movement to the arms 44—46, the carriage 38a will have forward movement imparted thereto which in turn imparts movement to the transfer paddle plate 32 in a forward direction. A suitable transversely extending shaft 47 projects between and is connected to the carriages 38a, 38b and has offset terminals to overlie the rear surfaces of the downwardly projecting lugs 32a on the transfer plate 32 and tends to limit the tilting movement of the plate. Fixed abutments 48 project inwardly from the bracket supports 41 adapted to, as the transfer paddle or plate 32 is moved by the carriages, contact against the free lower terminals 32a of the transfer paddle plate 32, whereby in the continued forward movement of the carriages 38a and 38b the said transfer plate 32 will be tilted about its axis to assume an upright position in the stacking chute.

The glove-abutment angle plate 33—34 is pivoted at 33a to the bottom wall of the stacking chute, and a spring-actuated arm 50 is connected to the under surface of that part 34 of this angle plate abutment and projects through a slotted opening in the bottom wall of the glove stacking chute for connection with a suitable spring 51 adapted to normally move the angle plate 33—34 when released by the transfer paddle plate 32 into a position whereby that portion 33 of the abutment angle plate—normally vertically disposed to constitute an abutment for the glove—will assume a flat position against the bottom wall of the stacking chute to permit the glove under the action of the transfer paddle plate 32 to readily pass over said abutment plate 33—34. In the reverse movement of the transfer paddle plate 32 the lower edge of the same will contact with the rear portion 34 of the glove-abutment angle plate and swing the latter about its pivotal support against the action of the spring connection so as to reposition that portion 33 of the abutment angle plate in glove abutting position, and in which position it is held, as previously described, by the engagement of the lower edge of the transfer paddle plate 32 with that portion 34 of the abutment angle plate. It will be noted that as the transfer plate 32 in the reverse movement thereof contacts with the part 34 the upper end of the transfer plate will be tilted rearwardly.

The driving mechanism for the transfer plate 32 and associated parts is preferably of a character to be controlled and set into operation automatically by the movement of the gloves through the ironing or pressing mechanism heretofore described; and a preferred embodiment of this feature of the invention will now be described.

A driving disc 30 is sleeved upon an extension of the large presser roll 5 at a point outside of what has been termed the rear side wall of the main frame of the machine and has a peripheral arm extension 81 to the free end of which is pivotally connected at 82 an elongated actuating rod 83 which latter is in turn pivotally connected at 84 to the upper end of a rock arm 85 having in turn pivotal connection at its lower end at 86 to that downwardly extending bracket 41 supported on the rear side wall of the main frame. The actuating rod 83 is threaded at its opposite ends and connects with its pivotal supporting terminals whereby to permit of lengthwise adjustment; and the pivotal connection 84 between the supporting bracket at the forward end of the actuating rod 83 and the rock arm 85 includes a bolt adapted to fit in one of the apertures 84a in said arm to permit of adjustment at this point of connection

at will. A carriage-actuating arm 87 is pivotally connected at 88 to the rock-arm 85 and at its opposite end to the carriage 38^b at this side of the machine, which carriage 38^b is connected by 5 a transverse rod 49 with the carriage 38^a and associated parts at the front side of the machine.

Arranged to rotate with the shaft 6 of the main presser roll at a point between the actuating disc 80 and the adjacent side wall of the frame work 10 is a ratchet wheel 89 adapted to be engaged by a tooth 90 upon a curved pawl 91 pivoted at 92 to the inner surface of said actuating disc 80, which pawl is normally held by a spring 93 so as to position its tooth 90 out of contact with said ratchet wheel 89. An adjustable abutment 94 is provided upon the side wall of the frame and adapted to, in one position of the pawl 91, contact with the free end thereof and move the tooth 90 of said pawl out of engagement with the tooth of the 20 ratchet wheel 89. The pawl 91 is adapted to be moved into position to engage its tooth with the tooth of the ratchet wheel 89 by a bell-crank lever 95 pivoted at 96 to the adjacent side wall of the main frame and having a pin 97 on the 25 free end of its actuating arm projecting through a slot 98 in the lower end of an arm 99 secured at 100 to the side wall of a piston cylinder 101 in which is positioned a coiled spring 102 sleeved upon the rod 103 of the piston and engaging between the piston head and the top wall of the cylinder. The upper end of said piston rod 103 is secured to a collar 104 sleeved upon an extension of the shaft 11 of the small presser roller 10. A locking dog 105 having an offset shoulder 106 30 to engage under the pin 97 of the bell-crank lever 95 is pivoted at 107 to the arm 99 and is normally maintained in locking engagement with said pin by a spring 108. A releasing pin 109 is secured on the outer surface of the actuating disc 80 and 35 is adapted in one of the positions of the disc to engage the free end of the locking dog 105 and move the same about its pivot 107 against the action of the spring 108 whereby to permit the bell-crank lever 95 to move about its pivotal connection 96 and permit the release of the pawl 91 40 from ratchet-holding engagement with the ratchet wheel 89. A spring 110 secured to the projecting arm 81 of the actuating disc 80 and to the adjacent side wall of the main frame, tends to move said 45 projecting arm of the disc in a rearward direction when the disc has been freed from locking engagement with the ratchet wheel 89, and this rearward movement of the disc arm 81 imparts rearward movement to the elongated actuating rod 83 and its connecting mechanism for imparting rearward movement to the carriages 38^a and 38^b operatively connected to the glove-transfer plate.

60 The operation of the driving mechanism above described may now be briefly reviewed.

Assuming that the large presser roll 5 is under constant rotation, through the medium of a motor or other power-drive mechanism, or hand-operating means, as desired, and that no gloves are at this time passing through the machine, no movement will be imparted to the actuating disc 80 and associated parts for driving the glove-stacking mechanism, for the reason that the 65 large presser roll 5 at this time freely rotates with respect to the actuating disc 80, and the tooth 90 of the pawl 91 is held out of engagement with the ratchet disc 89 which rotates with the driving shaft 6. Now, as the gloves are fed to the machine by being placed on the upper surface of the

feed belt 28, as each glove in turn assumes a position between the adjacent faces of the belt 28 and the belt 29 at a point between the large presser roll 5 and the upper relatively small presser roll 10, the glove causes the upper presser roll 10 to move upwardly, due to the thickness of the glove, and in this upward movement of the presser roll 10 the latter in turn carries upwardly the connected collar 104, piston cylinder 101, and connected arm 99. At this time the 85 shoulder 106 of the locking dog 105 carried by the arm 99 being in engagement with the pin 97 at the actuating end of the bell-crank lever 95, the lever will thereby be moved upon its pivot 96 so as to force the free end of the bell-crank lever 90 inwardly whereby to force the pawl 91 inwardly against the action of the spring 93 whereby to engage the tooth 90 of said pawl 91 with the tooth of the ratchet wheel 89. The ratchet wheel is now fixed for movement with the drive shaft of 95 the large presser roll 5. The actuating disc 80 will thereby be caused to rotate against the action of the spring 110 to impart forward movement to the actuating rod 83 and the parts operatively connected therewith. This movement 100 of the disc and actuating rod 83 in a forward direction will continue until the locking dog 105 for the bell-crank lever is engaged and moved out of engagement with the pin 97 of the bell-crank lever by pin 109 of the actuating disc 80; where- 105 upon the free end of the locking pawl 91 will contact with the abutment 94 thereby releasing the tooth 90 of the locking pawl 91 from locking engagement with the ratchet wheel 89, the spring 93 holding said pawl with its tooth out of 110 ratchet engagement; and the spring 110 will at this time impart a reverse movement to the actuating disc 80, and simultaneous rearward movement to the actuating rod 83 and the stacker mechanism. As will be understood, prior to the 115 reverse movement of the actuating disc 80, the presser roll 10 is moved downwardly by the spring 13, the arm 90 moving downwardly carrying with it the pawl 105, the shoulder 106 of the pawl being moved downwardly beyond the pin 97, and at 120 the beginning of the reverse movement of the actuating disc 80, said pawl will be returned by the spring 108 to normal position in advance of the return of the pin 97.

Means to indicate the number of gloves passing 125 through the machine, whereby to keep a check on the number of gloves operated upon as well as to assist the operator in checking the number of gloves to be boxed in each carton placed at the front end of the glove runway, will now be de- 130 scribed:

A bell 111 is positioned on one of the side walls of the machine, and arranged to cooperate with said bell is a striker arm 112 pivoted intermediate its ends at 113 to the side wall of the 135 machine; and said striker arm has a striker knob 114 normally held in contact with the bell by a spring 115 secured to the arm and to the adjacent side wall of the frame at 116. The opposite free end 112^a of the striking arm is ar- 140 ranged in the path of a pin 117 secured to one surface of a ratchet wheel 118 adapted to have intermittent movement imparted thereto by a spring-actuated pawl 119 mounted upon the inner surface of the actuating disc 80. The parts 145 are so constructed and arranged that in each movement of the actuating disc 80 in one direction the pawl 119 will engage with a tooth of the ratchet wheel 118 and impart movement to the latter the distance of one tooth. A spring 150

pawl 118a mounted on the side wall B holds the ratchet wheel against movement except when the ratchet wheel is actuated by the pawl 119. Assuming that the teeth of this ratchet wheel 5 118 correspond in number to the normal supply of gloves for each box or carton to be filled, it will be appreciated that the successive operations of the ratchet wheel 118, tooth by tooth, as each glove passes through the pressing mechanism, will result, when one complete revolution 10 of the ratchet wheel 118 is accomplished, in causing the pin 117 on said ratchet disc 118 to engage the free end 112a of the striker arm 112 and move the same downwardly; and the striker 15 knob 114 upwardly against the action of its connected spring 115. Now, as the striker arm is released from the pin 117 the bell will be sounded, thus apprising the operator that the necessary supply of gloves has passed through the machine 20 for that particular boxing operation.

Carton or box-supporting mechanism is associated with the glove runway or chute. The runway or chute at its forward end is of construction and size to have fitted over said inner 25 end the glove receiving box or carton 120. Elongated, horizontally disposed spring arms 121 are secured through the means of downwardly extending flanges 122 to the side walls of the runway or chute, and these spring arms assume 30 a position extending inwardly from and slightly spaced upwardly from the sides of the chute with the forward terminals 121a upwardly curved so that as the box is positioned over the front end of the chute the upper side of the box will 35 slip between the spring arms 121 and the upper edges of the sides of the chute. In assembling the box, that portion of the usual folded top which connects with the side of the box now disposed uppermost may be folded back as indicated 40 at 120a upon the uppermost side of the box whereby to engage beneath the spring arms 121 and thereby offer no obstruction at the open end of the box for the ready passage of the gloves along the chute and into the box. Suitable spacing 45 bars 123 may also be positioned upon the bottom wall of the chute adjacent the front end to be engaged by the lower side of the wall of the box and thereby space the inner surface of said 50 lower side of the box from the bottom wall of the chute and from the movable parts beneath the chute associated with the movable glove-abutment plate within the chute. These spacing bars 123 are inclined at the ends as illustrated at 123a, whereby to facilitate the ready 55 passage of the box over the end of the chute.

A general review of the operation of the machine follows

The machine having been placed in operation 60 through the medium of hand or motor power applied to the drive wheel fixed to the shaft 6 which carries the large presser roll 5, an operator takes the gloves as manufactured, and preferably promptly after they have left the hot form of the usual glove-forming mechanism, and places said gloves in spaced relation and in alternate arrangement, that is, "lefts" and "rights", upon the conveyor belt 28. The gloves as they move with the belt 23 between the surface of this belt and the cooperating belt 29, will be ironed or pressed in a substantially flat condition and free from wrinkles by reason of the pressure exerted as said gloves pass under the belts 28 and 29 between the presser rolls 5 and 10 and 20. The foremost ironed glove will

be delivered by that portion of the endless carrier 29 arranged beneath the presser roll 5 to the forward end of said conveyor which passes around the guide roll 23, and the glove will ride off said conveyor at this point onto the glove-transfer plate 32 which at this time assumes a rearward inclined position with the free upper end thereof in contact with that portion of the conveyor passing around the guide roll 23. At this time, also, the pivoted angle-abutment plate 33 will assume the position illustrated in Figure 3, with one flange of said angle plate projecting upwardly whereby to constitute an abutment for the glove as it slides down the transfer plate 32 as delivered from the belt 29. As a succeeding glove moves into position between the large presser roll 5 and the upper smaller presser roll 10, the glove transfer mechanism is automatically brought into operation, the connection between the upper presser roll 10 and the bell-crank lever 95, as previously described, in the rising movement of the presser roll 10 under the outward pressure of the glove therebelow, will move the pawl 91 into holding engagement with the ratchet 89 movable with the drive shaft 6 of the large presser roll 5, with the result that the actuating rod 83 will be moved forwardly and carry therewith the carriages 38a, 38b. As said carriages move forward, the transfer plate 32 having also been moved forwardly with said carriages 38a-38b, said transfer plate imparts movement to the glove lying upon said plate over and past the angle abutment plate 33, said abutment plate swinging about its pivot under the pressing action of the glove and transfer plate. The glove in contact with the transfer plate 32 will be positioned by the continued movement of the transfer plate into contact with the rearmost glove in a stacked series in the glove chute, generally indicated by the numeral 31.

At about this time the pawl 91 having been brought into contact with the abutment plate 94 will be moved with its tooth 90 out of engagement with the ratchet disc 89 thereby releasing the actuating disc 80 which under the action of the spring 110 will move the connected disc and actuating rod 83 rearwardly. The transfer plate 32 will, under the return movement of the actuating rod 83, assume a position with its free end in contact with the delivery end of the belt 29 whereby to receive a succeeding glove to be transferred and assembled with other gloves in the chute, said transfer plate being tilted rearwardly by gravity as soon as the lower projecting portions 32a of the plate are disengaged from the abutments 48. At this time the shoulder 106 of the locking dog 105 which was previously released by the abutment pin 109 to permit of the release of the pawl 91 from the ratchet 89, will again have assumed a position in contact with the pin 97 whereby to cause the subsequent tilting of the bell crank lever 95 so as to force the pawl 91 inwardly to engage the tooth 90 of the pawl with the ratchet 89 as a succeeding glove presses the small presser roll 10 upwardly and with it the piston and arm connections 99, 101, 102, 103, and 104. By reason of the piston connections just briefly referred to, a "safety" relief is provided to protect the parts 140 against undue pressure, etc.

When the desired number of gloves have been ironed and delivered, the operator will be apprised of this fact, due to the automatic operation of the signal 111, as previously described; 150

whereupon the operator will remove the specified number of gloves from the chute and place them in a box or carton.

What I claim is:

- 5 1. In a machine for pressing gloves and the like, the combination of cooperating movable presser members arranged to receive gloves therebetween, a signal, a movable actuating member for the signal operatively associated with one of said presser members, and one of said presser members being bodily movable under the action of the gloves passing between the presser members for imparting movement to said actuating member, and mechanism interposed between the actuating member and the signal for operating 80 the latter after a predetermined number of gloves has passed between the presser members.
- 10 2. In a machine for pressing gloves and the like, movable presser rolls, a signal, a movable actuating member for said signal operatively associated with one of said presser rolls to rotate therewith and normally stationary, one of said movable presser rolls being bodily movable under the action of the gloves in passing between the presser rolls for causing said actuating member to rotate with one of the presser rolls and thereby control the operation of the signal. 85
- 15 3. In a machine for pressing gloves and the like, the combination of movable presser rolls, one of said rolls being rotatable, and the cooperating presser rolls being rotatable as well as bodily movable with respect to the other roll, an indicator, and an actuating member for the indicator adapted to be moved by the rotatable roll to actuate the indicator, and means controlled by the bodily movement of the other roll for rendering said actuating member operative. 90
- 20 4. In a machine for pressing gloves and the like, the combination of a main presser roll, a bodily movable cooperating presser roll, a signal, an actuating rotatable member for said signal operatively associated with the main presser roll, and means controlled by the bodily movement of the cooperating presser roll for coupling the rotatable member with the first-named presser roll for rotation with the latter. 95
- 25 5. In a machine for pressing gloves and the like, the combination of a main presser roll adapted to rotate about a substantially fixed axis, a rotatable cooperating presser roll mounted for supplemental movement towards and from the main presser roll, a signal, an actuating member for the signal normally inactive and adapted to be coupled for movement with the main presser roll, an operative connection between said actuating member and the auxiliary presser roll adapted in the supplemental movement of the latter to connect the actuating member to the main presser roll for movement with the latter. 100
- 30 6. In a glove pressing machine, the combination of a main presser roll, a movably mounted auxiliary rotatable presser roll adapted to receive gloves therebetween to be pressed, a signalling mechanism operatively associated with and controlled by a non-rotatable movement of the auxiliary presser roll under pressure of articles passing between the rolls and whereby to indicate the number of pressed articles. 105
- 35 7. In a pressing machine, the combination of pressing mechanism including cooperating presser members one of which is rotatable as well as bodily movable, means for moving the pressed articles away from said pressing mechanism, means to indicate the number of pressed articles 110 passing between the presser members, and means associated with the pressing mechanism and controlled by the bodily movement of the bodily movable presser member whereby the operation of both the last mentioned means is governed and actuated in the movement of the articles through the pressing mechanism. 115
- 40 8. In a machine of the character described, the combination of pressing mechanism including cooperating rotatable presser members, a member at the side of one of the presser members rotatable with and independently of said presser member, and releasable clutching mechanism between said presser member and rotatable member, means actuated by the passing of the articles between said pressing members to engage said clutch to rotate said rotatable side member, and an indicator operated by the rotation of said side member. 120
- 45 9. In a machine of the character described, the combination of pressing mechanism including cooperating rotatable presser members, a member at the side of one of said presser members rotatable with and independently of said presser member, releasable clutching mechanism between said presser member and rotatable member, means controlled by the passing of the articles between said pressing members to engage said clutch to rotate said rotatable side member, article handling means to receive the pressed articles, actuated by the movement of said rotatable member, and a signal also actuated by the movement of said rotatable member. 125
- 50 10. In a machine of the character described, the combination of pressing mechanism including cooperating presser rolls, indicating means, a rotatable actuating member for the indicating means to the side of one of said rolls, coupling means between said actuating member and the adjacent presser roll, one of the presser rolls being movable towards and from the cooperating presser roll through the instrumentality of the passage of an article to be pressed between the presser rolls, and means associated with the last-mentioned roll for rendering active and inactive the coupling means according to the to and fro movement of said roll. 130
- 55 11. In a machine of the character described, the combination of cooperating presser rolls one of which is mounted for movement towards and from the other under the action of articles to be pressed passing from between the rolls, a signal, and means operatively associated with said signal and said presser roll whereby the signal is actuated from the translatory movement of the presser roll caused by the passage of articles under this member whereby to indicate the number of pressed articles. 135
- 60 12. In a machine of the character described, cooperating rotatable presser members adapted to receive therebetween articles to be pressed, one of said members being mounted for movement towards and from the other under the action of the article passing between said members, a signal, and a movable article-delivery member, and means for actuating the signal and delivery member from the translatory movement of the rotatable presser member caused by the passage of articles between the presser members. 140
- 65 13. In a pressing mechanism, the combination of cooperating rotatable presser members adapted to engage articles therebetween under pressure to press the same in the rotatable movement of said members, one of said rotatable members being mounted for relative movement towards and from the other member under the action of 145
- 70 14. In a machine of the character described, the combination of cooperating rotatable presser members adapted to receive therebetween articles to be pressed, one of said members being mounted for movement towards and from the other under the action of the article passing between said members, a signal, and a movable article-delivery member, and means for actuating the signal and delivery member from the translatory movement of the rotatable presser member caused by the passage of articles between the presser members. 150
- 75 15. In a machine of the character described, the combination of cooperating rotatable presser members adapted to receive therebetween articles to be pressed, one of said members being mounted for movement towards and from the other under the action of the article passing between said members, a signal, and a movable article-delivery member, and means for actuating the signal and delivery member from the translatory movement of the rotatable presser member caused by the passage of articles between the presser members. 155

- the articles passing between the members, an indicator, and mechanism interposed between the indicator and movable presser member to actuate the indicator after a predetermined number of movements of said movable presser member. 14. In a machine for pressing gloves and the like, the combination of cooperating movable presser members adapted to press articles therebetween, indicator mechanism normally inactive in the rotatable movement of the pressing member when no articles are being pressed, and an actuating means for said indicator mechanism operatively connected with and set into operation by one of said presser members by contact of the articles therewith, said actuating means being constructed and arranged to operate said indicator mechanism after a given number of pressing operations. 15. In a pressing machine, the combination of cooperating movable presser members adapted to receive therebetween and press articles, mechanism adapted to indicate the number of pressed articles, means interposed between one of said pressing members and the indicating mechanism for actuating the latter through the movement of said presser member, and means operatively connected with the other presser member for controlling the operation of said interposed means whereby the same is actuated as articles are pressed. 16. In a pressing machine, the combination of signal mechanism, a main rotatable presser member and a movable cooperating presser member to receive articles therebetween and press the same, and means governed by the progress of articles between said presser members for actuating the signal mechanism, comprising an actuating disc for the signal, and clutch mechanism between the main rotatable presser member and disc for coupling the disc thereto for movement therewith to control said signal mechanism, and an operative connection between said clutch mechanism and the cooperating presser member to control the clutch mechanism. 17. In a pressing machine, the combination of signal mechanism, a main rotatable presser member and a movable cooperating presser member to receive articles therebetween and press the same, and means governed by the progress of articles between said presser members for actuating the signal mechanism, comprising an actuating disc for the signal, and clutch mechanism between the main rotatable presser member and disc for coupling the disc thereto for movement therewith to control said signal mechanism, an operative connection between said clutch mechanism and the cooperating presser member to control the clutch mechanism, and movable delivery mechanism for the pressed articles having an operative drive connection with said disc whereby the delivery mechanism is rendered operable by the movement of said disc. 18. In a pressing machine, the combination of a main rotatable presser member, a cooperating movable presser member, said members adapted to receive therebetween articles to be pressed, stacking mechanism for the pressed articles, indicating mechanism, an actuating disc common to the stacking mechanism and the indicator mechanism, and clutching mechanism between the main rotatable presser member and the disc for coupling the disc thereto for movement therewith to control the movement of the indicator mechanism and the stacking mechanism, and an operative connection between said clutching mechanism and the cooperating presser member whereby the clutching mechanism is controlled by said cooperating presser member. 19. In a pressing mechanism, the combination of a main presser roll, a cooperating presser roll, signal mechanism, an actuating disc operatively associated with the signal mechanism for operating the latter, a ratchet wheel rotatable with the main presser roll, and a movable dog carried by the actuating disc for engaging said ratchet wheel, operatively associated with and controlled by said cooperating roll whereby to actuate the disc as articles are pressed. 20. In a pressing mechanism, the combination of a main presser roll, a cooperating presser roll, signal mechanism, an actuating disc operatively associated with the signal mechanism for operating the latter, a ratchet wheel rotatable with the main presser roll, and a movable dog carried by the actuating disc for engaging said ratchet wheel operatively associated with and controlled by said cooperating roll whereby to actuate the disc as articles are pressed, said disc having an arm extension, article stacking mechanism and a driving connection for the latter connected to said arm extension whereby the stacking mechanism is rendered operative under the movement of said disc. 21. In a pressing machine, the combination of a main presser member, a rotatable roll cooperating therewith and mounted for bodily movement with respect to the main presser member as articles pass therebetween, a rotatable shaft, signal mechanism, a ratchet mounted on the shaft for rotation therewith, a normally stationary actuating disc on the shaft, a dog carried by the disc to engage the ratchet to couple the disc to the ratchet for rotatable movement with the latter, a connection between the disc and signal mechanism, and means for actuating the dog operatively connected with and controlled by the bodily movement of the rotatable roll. 22. In a pressing machine, the combination of a main rotatable roll, a cooperating rotatable roll mounted for bodily movement under the action of articles passing therebetween, a normally stationary rotatable actuating disc, signal mechanism operatively associated with the actuating disc and controlled by the movement of said disc, a releasable clutching mechanism between said actuating disc and the main presser roll for causing rotatable movement of the actuating disc with the main roll, whereby to control the signal mechanism, and means interposed between said clutching mechanism and cooperating roll for actuating the clutching mechanism by the bodily movement of said roll. 23. In a pressing machine, the combination of a main rotatable roll, a cooperating rotatable roll mounted for bodily movement under the action of articles passing therebetween, mechanism for delivering and stacking the pressed articles, a normally stationary rotatable actuating disc, signal mechanism operatively associated with the actuating disc and controlled by the movement of said disc, a releasable clutching mechanism between said actuating disc and the main presser roll for causing rotatable movement of the disc with the main roll, whereby to control the signal mechanism, means interposed between said clutching mechanism and cooperating roll for actuating the clutching mechanism by the bodily movement of the roll, and driving connection for said delivery and stacking mechanism.

- having connection with said disc whereby the delivery and stacking mechanism are operable only as the disc is operable and whereby the signal mechanism will indicate the passage of a predetermined number of articles between the pressing rolls. 80
24. In a pressing machine, the combination of a main rotatable presser roll, a cooperating rotatable presser roll mounted for bodily movement under the action of articles passing therebetween to be pressed, a rotatable actuating disc to the side of and normally disconnected from the main presser roll, means interposed between the disc and the main presser roll for coupling the same for rotation together, signalling mechanism operatively connected to the disc for actuation through the movement of the latter, and means for actuating said coupling means operatively associated with and governed by the cooperating roll in its bodily movement under the action of articles passing between the rolls. 85
25. In a pressing machine, the combination of a main presser roll, an auxiliary presser roll movable towards and from the main presser roll under the action of articles passing between the rolls, an actuating disc arranged to the side of the main presser roll, signal mechanism operatively controlled by the rotatable movement of the disc, and releasable means for connecting said disc to the main roll operatively connected with and controlled by the movement of the said auxiliary presser roll. 90
26. In a pressing machine, the combination of a main presser roll, an auxiliary presser roll movable towards and from the main presser roll under the action of articles passing between the rolls, an actuating disc arranged to the side of the main presser roll, signal mechanism operatively controlled by the rotatable movement of the disc, releasable means for connecting said disc to the main roll operatively connected with and controlled by the movement of the said auxiliary presser roll, stacking mechanism for the pressed articles, and driving means for the stacking mechanism connected with and operable only under the action of said disc. 95
27. In a pressing machine, the combination of a main presser roll, an auxiliary presser roll movable towards and from the main presser roll under the action of articles passing between the rolls, an actuating disc arranged to the side of the main presser roll, a signal, operating means therefor operatively connected with the disc for actuation after a predetermined number of movements of the disc, and releasable means for connecting said disc to the main roll, operatively connected with and controlled by the movement of the auxiliary presser roll. 100
28. In a pressing machine, the combination of a main presser roll, an auxiliary presser roll mounted for bodily movement, signalling mechanism, movable actuating means for the signal, means for imparting movement to the actuating means according to each movement of the auxiliary roll under the action of articles passing therebeneath, and means whereby the signal will operate only after a predetermined number of movements of the actuating means as moved by the movement of the cooperating roll. 105
29. In a pressing machine, the combination of a main presser member and an auxiliary cooperating rotatable presser roll mounted for bodily movement, signalling mechanism, stacking mechanism, an actuating member for the signalling mechanism and the stacking mechanism, a connection between the bodily movable roll and the actuating means and between the actuating means and the stacking mechanism whereby upon each bodily movement of the roll the stacking mechanism will be operated, and a connection between the actuating means and the signalling mechanism whereby the latter will be operated only after a plurality of operations of said stacking mechanism under the action of said actuating means. 110
30. In a glove pressing machine, the combination of a main presser roll, an auxiliary presser roll mounted for movement towards and from the main presser roll, signalling mechanism, and means for operating the latter after a predetermined number of gloves have been pressed, said means being operatively connected with and controlled by the movement of the auxiliary presser roll towards and from the main presser roll. 115
31. In a glove pressing machine, the combination of a main presser roll, an auxiliary presser roll mounted for movement towards and from the main presser roll, signalling mechanism, and means for operating the latter after a predetermined number of gloves have been pressed, the said means being operatively connected with the main presser roll, and an actuating member for said means operatively connected with and governed by the movement of the auxiliary presser roll away from the main presser roll under the pressure of the gloves. 120
32. In a pressing machine, the combination of glove stacking mechanism, glove pressing mechanism, the latter comprising cooperating rotatable pressing members one of which is bodily movable with respect to the other, and signalling mechanism associated with the presser members to indicate after a particular number of gloves have been stacked, a connection between the stacking mechanism and the bodily movable presser member whereby the stacking mechanism is set into operation by the bodily movement of the presser member, whereby both the signalling and the stacking mechanisms are controlled by the outward pressure of the bodily movable member under the action of the gloves passing between the presser members. 125
33. In a pressing machine, the combination of a main presser member, an auxiliary cooperating rotatable presser member to receive gloves therebetween and press the same, the auxiliary presser member being mounted for movement towards and from the main presser member under the action of the gloves passing between the members, and signalling mechanism operatively associated with the pressing mechanism and adapted to impart a signal only after a plurality of outward movements of the auxiliary presser member under the action of the gloves whereby to indicate after a predetermined number of gloves have been pressed. 130
34. In a machine of the character described, the combination of a glove runway adapted to support at its discharge end a glove-receiving box, glove pressing mechanism, glove stacking mechanism arranged between the discharge end of the runway and the glove pressing mechanism to receive the pressed gloves from the pressing mechanism and stack the same and deliver the stacked gloves into the supported box, signalling mechanism for operating after a predetermined number of pressed gloves have been delivered to said box, and actuating mechanism for operating the stacking and signalling mechanism. 135
- 75

through the action of the gloves in the pressing operation.

35. In a machine of the character described, the combination of cooperating presser members 5 adapted to receive therebetween articles to be pressed, an indicator, delivery means for the pressed articles, actuating means for the indicator, and associated actuating means for the delivery mechanism, said actuating means being 10 normally inactive, and means governed by the passage of the articles between the presser members for actuating each of said actuating means.

36. In a glove pressing machine, the combination of cooperating presser members adapted to receive therebetween gloves or articles to be pressed, means for delivering gloves in succession between said presser members, a signal, the 80 presser members being relatively movable with respect to one another under the action of the gloves passing therebetween, and means governed by said relative movement to actuate said signal after a predetermined number of gloves have 85 passed between the presser members.

CALVIN JOHN SHIMER.
